CONTROLLER FOR ELECTRICAL CIRCUITS

John E. Coffin, Maplewood, N. J., assignor to
Electric Arc Cutting & Welding Co., Newark,
N. J.

Application May 14, 1932. Serial No. 611,353

5 Claims. (Cl. 200—8)

This invention relates to the design of a controller for electrical circuits. In the use of such a controller as herein described, the current may be subdivided at the controller and distributed thereby to a plurality of circuits, or all of the current may be sent out over one or more single circuits, in accordance with the manner in which the drum of the controller is constructed.

I have found that my controller is especially desirable and useful in connection with arc welding systems, especially of the type set forth in Holslag application Serial No. 609,375, filed May 5, 1932, wherein the entire current is brought to the drum of the controller and distributed by it to the multiple circuits shown in said application.

Therefore, the principal object of my invention is to provide a controller which is relatively simple and inexpensive in design, yet one that is highly efficient in its operation.

Another object of my invention is to provide a controller which is so constructed that the parts may be readily reached for the purpose of adjusting the various contacts, or for renewal of any parts of the controller.

My invention will be readily understood by reference to the annexed drawing, wherein:

Figure 1 is a perspective view of the complete controller.

Figure 2 is a view looking down on the top of the controller, only two of the contact members being indicated, but the position of the others being indicated by the broken lines.

Figure 3 is a view on the line 3—3 of Figure 2.

In the drawing, wherein like numbers refer to corresponding parts in the various views, 1 is a framework having end support members 2 and 3. Rotatably mounted between the end members 2 and 3 is a shaft 4 having some operating means, as a hand-wheel 5, on one end thereof. Carried on the shaft 4, is a cylindrical drum 6. As shown more particularly in Figure 3, two U-shaped members 7 are fastened in any satisfactory manner, as by screws 8, to the opposite ends of the drum 6. Preferably, the two members 7 are in contact with each other near the axis of the drum 6, and the shaft 4 passes through both the members 7. While I prefer to use two members 7, I have built controllers using only one.

Mounted between the end members 2 and 3, is a support member preferably in the form of a polygonally-shaped metal rod 9 which extends parallel to the shaft 4 in the drum 6. If the rod 9 is of metal, it is covered with an insulator 10 preferably all in one piece, although it is obvious

that it may be made of several pieces, and around the insulator 10 are clamped a plurality of contact members which are shown made of two sections 11 and 12 both preferably of good conducting material. As shown in Figure 3, the section 11 is clamped to the insulator by a clamping bolt 13.

The section 12 is provided with a pivot pin 14 positioned in a slot in the section 11, and is held thereto by adjusting stud 15 which is threaded at 16 so that it can be adjusted in the section 11 to vary the tension of the spring 17 held in place between the collars 18 and 19. As a matter of fact, the section 12 is composed of at least two pieces, a channel-shaped member 20 and a contact piece 21 fastened thereto in any satisfactory manner as by one or more screws 22. The contact members comprising the two sections 11 and 12 are carried on the support member or rod 9 and insulator 10 in such a manner that the contact member 21 extends over the drum 6 and is adapted to rub on the surface of the drum 6.

In order to determine the time at which the various circuits through the several contact pieces 21 will be completed, the drum is cut out at 80 different portions indicated by the numbers 23, 24, 25, etc. Preferably, one or more of the contact pieces 21 are either in contact with the controller all the time, or they make contact with the controller on the first step thereof, so that 85 the current from the circuit is brought to the drum by one or more of these contact members and then distributed to the various circuits connected to the other contact members by means of lead wires connected to the clamping nuts 26 90 and controlled by the cuts or notches 23, 24, 25, etc., which are arranged as desired.

In order to position the drum for the different settings, a plurality of notches 27 are provided preferably at one end as indicated in Figures 1 95 and 2, and these notches cooperate with one of the contact pieces 21, which is not included in any circuit, to give certain positive and well-defined steps to the different settings of the controller. The drum is preferably made of good 100 conducting material, preferably hard drawn copper or bronze, and likewise the fingers 21 and their cooperating parts, as has already been referred to.

As will be readily understood, the contact members are quickly adjustable longitudinally on the support member 9 so as to line up with their respective notches in the drum 6, and by reason of the separate clamping piece 28, which is provided with a finger 29 to engage a finger 30 on 110

the section 11, any one of the contact members may be readily removed or applied to the support member without disturbing any of the other contact members. In addition, the drum 5 is so mounted on the shaft 4 that the shaft 4 can be quickly withdrawn from the frame and the drum, so that the entire drum 6 may be taken out and another drum substituted in order to quickly meet the circuit requirements which may 10 come up.

From what has been said, it will be seen that I have provided a controller that is very easy to construct, assemble, and dis-assemble, yet one that is highly efficient in operation.

15 Having thus described my invention, what I claim is:

1. A controller for electric circuits including a frame, a metallic cylinder positioned between the ends of the frame, at least one cross-bar positioned at each end of the cylinder and fastened at both ends to the cylinder, a shaft extending through said cross-members at the axial center of the cylinder, and directly connected to at least one of said cross-pieces, a metallic rod supported 20 by the ends of the frame and extending parallel with the cylinder, an insulator covering said rod, a plurality of contact members longitudinally adjustably carried on said rod and insulator and extending in contactual position with said cylinder, said cylinder being cut away around its periphery in alignment with the different contact members according to the requirements of its circuit, at least one of said contact members being 25 in continuous engagement with the periphery 30 of the cylinder when the same is in circuit, to

bring the current for distribution directly to the cylinder.

2. A controller for electric circuits as set forth in claim 1, further characterized in that the cylinder has one row of notches therein cooperating with one of said contact members to act as a step-positioning means. 80

3. A controller for electric circuits as set forth in claim 1, further characterized in that said rod and insulator are polygonal in shape, and each of said contact members has a part clamped around said insulator, and further characterized in that the cylinder at one end has a row of notches therein cooperating with one of said contact members to act as a step-positioning means. 85

4. A controller for electric circuits as set forth in claim 1, further characterized in that said rod and insulator are polygonal in shape, and each of said contact members is composed of two major metallic sections, one section being clamped around said insulator, the other section being pivotally and adjustably mounted on the first section, and means including notches in the cylinder for positively positioning the rotary movement of the cylinder in steps. 90

5. A circuit-controller as set forth in claim 1, further characterized in that said contact members are constructed so any one may be individually removed from said support rod without disturbing the others, and further that the drum is 105 carried on a shaft which may be readily and quickly removed from the frame and drum for the purposes described. 100
